UNITED STATES PATENT OFFICE

2,422,759

HONE

Lawrence O. Thrun, Pine City, Minn.

Application March 23, 1945, Serial No. 584,325

4 Claims. (Cl. 51—194)

1

This invention relates to a hone and more particularly to a hone adapted to be utilized in conjunction with emery cloth for machine operation, such, for example, as the honing of holes.

A primary object of this invention is the provision of an improved hone, characterized by adjustability of size, effected by varying thicknesses of emery cloth on the exterior thereof, taken from a supply positioned interiorly of the hone.

An additional object of the invention resides in the provision of a hone characterized by improved means for securing the same in related assembly, whereby after the thickness of the emery paper is adjusted as desired, the same may be held in position securely and effectively, yet readily released for readjustment when necessary.

A further and very important object of the invention resides in the provision of means in association with such a hone, whereby in the event of imperfect adjustment the hone is prevented from sticking or jamming in the hole.

An additional object of the invention is the provision of a hone characterized by an exterior casing, having a slight resiliency thereto, permitting sufficient play to insure proper operation, in the event that the thickness of the emery paper or the like on the exterior thereof is greater than necessary.

Still other objects reside in the provision of a hone which will be sturdy and durable in construction, reliable and efficient in operation, and relatively simple and inexpensive to manufacture and assemble.

Other objects reside in the combinations of elements, arrangements of parts, features of construction, all as will be more fully pointed out hereinafter and shown in the accompanying drawing, wherein there is disclosed a preferred embodiment of this inventive concept.

In the drawing:

Figure 1 is a side elevational view of one form of hone embodying the features of this inventive concept.

Figure 2 is a view partially in elevation and partially in longitudinal section of the hone shown in Figure 1.

Figure 3 is an enlarged sectional view taken substantially along the line 3—3 of Figure 1, but disclosing the emery cloth utilized in association with the device in position.

Figure 4 is an enlarged sectional view taken substantially along the line 4—4 of Figure 1 and viewed in the direction indicated by the arrows.

Figure 5 is a side elevational view of a modified

2

form of hone embodying features of this invention.

Figure 6 is a longitudinal sectional view of the device disclosed in Figure 5.

Figure 7 is an elevational view of a constructional detail.

Figure 8 is a sectional view taken substantially along the line 8—8 of Figure 5 as viewed in the direction indicated by the arrows.

Figure 9 is a sectional view taken substantially along the line 9—9 of Figure 5 as viewed in the direction of the arrows.

Figure 10 is a sectional view taken substantially along the line 10—10 of Figure 5, viewed in the direction indicated by the arrows, and

Figure 11 is a sectional view taken substantially along the line 11—11 of Figure 5, as viewed in the direction indicated by the arrows.

Similar reference characters refer to similar parts throughout the several views of the drawing.

Having reference now to the drawing and more particularly to the construction shown in Figures 1 to 4 inclusive, it will be seen that the device is comprised of a shank 20, having integrally associated therewith a collar 21, provided with a peripheral bevel 42. The shank 20 includes an extending portion 23, provided with a longitudinally extending slot 24, and terminates in the threaded extremity 25. Surrounding the portion 23 of the shank 20 is a sleeve 26, provided with a longitudinal slot 27, and interiorly beveled as at 28 and 29. Bevel 28 is adapted to coact with the bevel 22 of flange 21, while a beveled collar 30 coacts with the bevel 29 in a manner to be more fully pointed out hereinafter. A nut 31 is adapted to engage the threaded portion 25 exteriorly of the collar 30.

Extending from the extremity of the slot 27, about an arc of approximately 90° of the cylinder are circumferential cuts or slots 32.

From the foregoing the operation of the device should be readily understandable. Emery cloth 33 is passed through the slot 27, and engaged in the slot 24. Loosening of the nut 31 permits the members 30 and the bevel 22 to disengage from their associated bevels 28 and 29, to permit the rotation of the shank 20 with respect to the sleeve 26. Through means of this rotation the thickness of emery paper about the exterior periphery of the sleeve 26 may be readily changed, and when the desired thickness is achieved, tightening of the nut 31 will cause the parts to lock through the wedging action of the bevels previously described, and the device is ready for use.

The circumferential slots 32 provide a segment 34 of the device which is relatively resilient, in such manner that in the event too much emery paper is positioned on the outside of the device for a given job, a certain amount of play is permitted in the sleeve, in order that the honing may be effected without sticking of the device in the hole.

Having reference now to the modification disclosed in Figures 5-11 inclusive, there is shown at 40 a shank, provided with two longitudinal slots 41 and 42, and having a groove 43 peripherally thereabout adjacent one extremity. The opposite end of the shank 40 is threaded as at 44 and provided with a key 45 for a purpose to be more fully described hereinafter.

Adapted to be positioned around the shank 40 is a sleeve 46, provided with a longitudinal slot 47, adapted to coact with the slot 41 in a manner similar to the previously described slots 24 and 27, and a second slot (not shown) adapted to coact in a similar manner with the slot 42.

The slot 47 has circumferential slots 48 adjacent its extremities which serve a similar purpose to the previously described slots 32.

A portion 49 of the bore of sleeve 46 is enlarged, as at 50, and is adapted to encircle a split ring 51, seated in the annular groove 43 of the shank 40 when the parts are in related assembly. The opposite end of sleeve 46 is interiorly beveled as at 52, and is adapted to be engaged by bevel 53 on a collar 54, which has an interior channel 55 adapted to coact with the key 45. A nut 56 is positioned on the extremity of the device beyond the collar 55.

The operation of this form of device is substantially similar to that previously described, in that emery cloth or the like is adapted to be passed through the slots 47 and 41, and suitably adjusted by rotation of the shank 40, this being effected by loosening the nut 56. It will be seen that when the nut 56 is loosened, the bevels 52 and 53 may be separated in such manner as to permit relative rotation of the shank 40 in the sleeve 46. It will also be seen that when the nut is tightened, such relative movement is impossible.

This form of device may be readily disassembled by removal of the nut 56, and collar 54, passing the shank rearwardly until the split ring 51 is exterior of the enlarged portion 50 of the sleeve, whereupon the split ring will drop off and the device may be readily and completely disassembled.

From the foregoing it will now be seen that there is herein provided a device accomplishing all the objects of this invention, and others including many advantages of great practical utility and commercial importance.

As many embodiments may be made of this inventive concept, and as many modifications may be made in the embodiment hereinbefore shown and described, and it is to be understood that all matter is to be interpreted merely as illustrative and not in a limiting sense.

I claim:

1. In an abrading tool, a shaft about which

a roll of abrading material is adapted to be wound, a sleeve supported in spaced concentric relation to the shaft, said sleeve having an elongated longitudinal aperture in its periphery through which the abrading material is adapted to be payed out from the roll and wound about the sleeve to form a substantially cylindrical abrading surface on the exterior of the sleeve, said sleeve having a plurality of elongated transverse apertures communicating with the longitudinal apertures to form a yielding surface for the support of the abrading material.

2. In an abrading tool, a shaft about which a roll of abrading material is adapted to be wound, a sleeve supported in spaced concentric relation to the shaft, said sleeve having an elongated longitudinal aperture in its periphery through which the abrading material is adapted to be payed out from the roll and wound about the sleeve to form a substantially cylindrical abrading surface on the exterior of the sleeve, said sleeve having an elongated transverse aperture communicating with each end of the longitudinal aperture to form a yielding surface for the support of the abrading material.

3. In an abrading tool, a shaft about which a roll of abrading material is adapted to be wound, a sleeve supported in spaced concentric relation to the shaft, said sleeve having an elongated longitudinal aperture in its periphery through which the abrading material is adapted to be payed out from the roll and wound about the sleeve to form a substantially cylindrical abrading surface on the exterior of the sleeve, said sleeve having an elongated transverse aperture communicating with the longitudinal aperture to form a yielding surface for the support of the abrading material and means to hold the sleeve and shaft against relative motion.

4. In a device of the character described, a shank, a sleeve supported in spaced concentric relation with said shank, said sleeve having an elongated longitudinal aperture therein and a transverse elongated aperture extending from each end of the longitudinal aperture to a point substantially 90° therefrom to establish resiliency in a portion of said sleeve and means for locking said sleeve and shank against relative rotation.
